CLAIM

The ornamental design for the railing spacer, as shown.

DESCRIPTION

FIG. 1 is a top, front isometric view of the railing spacer; FIG. 2 is an end view thereof, the other end being identical; FIG. 3 is an enlarged fragmentary top plan view thereof; FIG. 4 is an enlarged fragmentary bottom plan view thereof; and,
FIG. 5 is a side elevation view thereof, the other side being identical.

The claimed design is shown fragmented for ease and clarity of illustration.
